UNITED STATES PATENT OFFICE.

RICHARD H. FULLAWAY, OF LOS ANGELES, CALIFORNIA.

HYDROCARBON-BURNER.

SPECIFICATION forming part of Letters Patent No. 699,380, dated May 6, 1902.

Application filed October 31, 1901. Serial No. 80,698. (No model.)

To all whom it may concern:

Be it known that I, RICHARD H. FULLAWAY, a citizen of the United States, residing at Los Angeles, in the county of Los Angeles, State 5 of California, have invented new and useful Improvements in Hydrocarbon-Burners, of which the following is a specification.

My invention relates, primarily, to oil-burners for use in locomotive-engines in which 10 crude petroleum and steam are used as a fuel and are not commingled in the burner; and the objects thereof are to provide a burner which is of simple construction and will atomize all the oil which issues from the burner.

15 In the locomotive oil-burners with which I am acquainted more or less oil finds its way to the bottom of the fire-box, where it is not consumed and is wasted. I avoid this waste 20 of oil by the burner described herein and illustrated in the accompanying drawings, in which—

Figure 1 is a perspective view of one-half of my improved burner cut longitudinally and vertically. Fig. 2 is a perspective view 25 of the oil-atomizing anvil which forms the front of the steam-chamber.

In the drawings, A is the casing of the burner, which is divided by the integral partition B into two parallel horizontal longitudinal chambers C and D, which are disposed one 30 above the other, the upper chamber being the oil-chamber and the lower one the steam-chamber. These chambers terminate on the same vertical line, and discharge-ports E and F 35 of these chambers are parallel and horizontal. The front of the steam-chamber may be closed by the adjustable oil-uncovered anvil-block G, by means of which the size of the steam-port F is regulated. This anvil-block projects in front of the steam-port and its upper 40 surface inclines upward at an angle of substantially ten degrees, so that the steam is directed slightly upward. The oil is discharged upon the steam, and should any of 45 the oil pass through the steam it will be caught by the anvil-block and will still be subjected to the atomizing effect of the steam and will

be carried out with the steam and burned. The anvil-block also provides a surface against which the larger and heavier particles of oil may be hurled to break them into atoms, which will readily burn. The oil and steam chambers are connected with a suitable oil-supply and steam-supply (not shown) in the usual well-known manner through openings provided in the casing.

Having described my invention, what I claim as new, and desire to secure by Letters Patent, is—

1. A hydrocarbon-burner consisting of a 60 casing having a partition arranged to divide the interior thereof into two parallel longitudinal chambers, terminating on the same vertical line, and provided with ports, the lower of said chambers having a vertically- 65 adjustable uncovered anvil-block, whose upper surface projects in front of said chamber at an angle.

2. A burner, composed of an oil-chamber disposed above a steam-chamber, both of said 70 chambers having ports which open on the same vertical line, said steam-chamber having its front composed of an uncovered anvil-block whose upper surface projects upward at an angle to the central line of the steam- 75 chamber.

3. In a burner in which oil and steam are discharged into the fire-box from separate chambers, having ports terminating on the same vertical line, the oil-chamber being disposed above the steam-chamber; an uncovered anvil-block extending across and at the lower edge of the steam-port; said anvil-block having its upper surface projecting in front of the steam-port, upwardly at an angle to a 80 plane which is parallel with the center line of the steam-chamber.

In witness that I claim the foregoing I have hereunto subscribed my name this 25th day of October, 1901.

RICHARD H. FULLAWAY.
